UNITED STATES PATENT OFFICE.

AUGUSTUS C. SCHOOLEY, OF CHICAGO, ILLINOIS.

PAPER-FILE HOLDER.

SPECIFICATION forming part of Letters Patent No. 294,279, dated February 26, 1884.

Application filed November 15, 1883. (No model.)

To all whom it may concern:

Be it known that I, AUGUSTUS C. SCHOOLEY, of Chicago, in the county of Cook and State of Illinois, have invented certain new and useful 5 Improvements in Newspaper-Files; and I do hereby declare that the following is a full, clear, and exact description thereof, reference being had to the accompanying drawings, and to the letters of reference marked thereon, which form 10 a part of this specification.

This invention relates to devices intended more especially for filing newspapers and other similarly-folded sheets, and has for its object to provide a desirable construction, whereby 15 the different leaves or folios belonging to the same paper will lie contiguous to each other in the mass of filed sheets, so that in passing from one folio to the next of the same paper it will be unnecessary to turn over intervening 20 sheets on the file, as is common in devices heretofore employed for filing newspapers.

The invention consists in the matters set forth in the following description and in the appended claims.

25 In the drawings, Figure 1 is a perspective view of a file constructed in accordance with my invention. Fig. 2 represents the principal part or body of the file with the holding device detached therefrom. Fig. 3 is a view of 30 the holding device detached and having parts broken away to show the passages for the puncturing-wires. Fig. 4 is a transverse section of the parts applied to each other as in use, said section being taken through the axis 35 of one of the puncturing-wires.

In the particular form of my invention shown in said drawings, A is a longitudinal bar, forming the back and principal part of the body of the structure.

40 A' is a flange projecting from the lower edge of the back A, and at right angles therewith, being usually a separate strip attached to said lower edge of the back A. Fastened to said flange-strip A' are any desired number of 45 puncturing-wires, a², rising parallel with the inner face of the back A at a suitable distance therefrom, and preferably extending above the upper edge of said back, as better seen from Figs. 2 and 4. Blocks a and a' are fastened to the back A and flange-strip A' at the

ends of the latter, and provided with studs a², rising parallel with the puncturing-wires a³.

B is a strip or bar forming the principal part of the holder. It is constructed to extend over the blocks a and a' and over the back 55 A, and is provided with holes a⁴ and a⁵, to admit the ends of the puncturing-wires a³ and studs a².

B' is a presser-strip of the same width as the projecting part of the flange-strip A', and 60 of suitable length to set down over the latter and between the end blocks, a and a'. The presser-strip B' is connected with the bar B by means of springs, which are preferably of the form shown at B', or of bent flat metal, arranged longitudinally of the bar B and presser-strip B'. Said springs are desirably attached centrally to the bar B by screws or rivets, and to the presser-strip B' by screws b, which pass through slots b' in the springs, 70 whereby the latter may freely move on said presser and allow the latter to approach the bar B as the papers accumulate in the file. The presser B' is also provided with holes a⁴, to admit the puncturing-wires a³. Spring-catches A² are applied to the end blocks, a and a', or elsewhere to the body of the file, in 75 position to engage the bar B. As herein shown, said springs are attached to the end blocks and engage the ends of the said holder-bar. A clamp-hook, A³, is hinged to the central part of the back A in position to swing over the middle of the bar B, to hold the same 80 down upon the back in opposition to the force of the presser-springs B', which tend to lift 85 said bar at this point, particularly when the file is filled, or nearly so. Said bar B may, however, be made stiff enough to not require this clamp; or the retaining springs or clamps may obviously be arranged opposite the points 90 where the presser-springs B' are attached to said bar, so as to render other retaining devices unnecessary.

In the use of the file the holder B B' is detached from the body, and the folded sheet is 95 pressed down over the points of the puncturing-wires near the fold in the sheet, after which the holder is pressed down over said wires a³ and studs a² and secured by the springs A² and clamps A³. The presser-strip B' is thus 100

made to bear upon the fold of the sheet throughout its length, clamping it firmly against the opposing flange A'. Succeeding papers are applied in a similar manner over those previously filed, and each sheet or folded paper has its several parts or folios adjacent to each other without reference to the number of papers upon the file.

In the arrangement of the spring-catches A² and studs a² as shown in the drawings, the latter are of proper length to enter the holes a³ of the bar B before the latter encounters the spring-catches, and they therefore serve as guides and steady-pins to prevent the lateral displacement of said bar while being forced into engagement with the catches.

The several longitudinal parts of the file may manifestly be made of sheet metal and stiffened by being ribbed in the usual manner; or said parts may be of light wood, as indicated by their proportions as shown in the drawings.

It will obviously not be a departure from my invention if the parts B and B' are not connected in a unitary part, as shown. The springs B² should, however, in this case be attached to one of said parts, and, on the whole, the connection of the parts B and B' by the springs, as shown, is desirable for convenience in manipulation. The holder-bar B is not necessarily of the length shown for the mere purpose of retaining the presser, nor is such a bar at all essential for this object; but it is preferably present and of the dimensions set forth, as a matter of convenience in applying the presser to the body, and also as furnishing a shield to the points of the puncturing-wires a³, though to this latter end it is not important

that holes a⁴ should be provided therein for said wires, since said wires may be shorter 40 than they are shown—as, for example, rising only to the height of the back A.

I claim as my invention—

1. The combination, with the back A, flange-strip A', and puncturing-wires a³, forming the 45 essential parts of the body, of a presser, B', and springs B², and devices for detachably securing the presser to the body, substantially as described.

2. The combination, with the back A, flange-strip A', and puncturing-wires a³, of a bar, B, presser B', springs interposed between the bar and presser, and devices for holding the bar upon the body, substantially as described.

3. The combination, with the back A, flange-strip A', puncturing-wires a³, and end blocks, a a', of the presser-strip B', fitted to drop over the wires a³ and between the end blocks, a bar, B, fitted to rest on the end blocks, springs B², interposed between the bar B and the presser 60 B', and spring-catches A², arranged to engage the bar B to the body of the structure, substantially as described.

4. The combination, with the body and the bar B for holding the presser, of spring-catches 65 arranged to engage the ends of said bar, and a detachable clamp arranged to secure the middle of said bar to the body, substantially as described.

Chicago, November 5, 1883.

AUGUSTUS C. SCHOOLEY.
